UNITED STATES PATENT OFFICE.

WARD S. IRELAND, OF OWENSBORO, KENTUCKY.

TYPE-WRITING MACHINE.

1,098,117.

Specification of Letters Patent. Patented May 26, 1914.

Application filed March 11, 1913. Serial No. 753,634.

To all whom it may concern:

Be it known that I, WARD S. IRELAND, a resident of Owensboro, in the county of Daviess and State of Kentucky, have invented certain new and useful Improvements in Type-Writing Machines; and I do hereby declare the following to be a full, clear, and exact description of the invention, such as will enable others skilled in the art to which it appertains to make and use the same.

This invention relates to improvements in typewriting machines,—the object of the invention being to provide means whereby the key lever structure and key board shall be maintained firm, rigid and stable and also to provide efficient means for accurately guiding the key levers in their movements.

With this object in view, the invention consists in certain novel features of construction and combination of parts as hereinafter set forth and pointed out in the claims.

In the accompanying drawings; Figure 1 is a sectional view of a portion of a typewriting machine illustrating an embodiment of my invention; Fig. 2 is a rear elevation of the key lever mounting, and Fig. 3 is a perspective view of said mounting.

1 represents the frame of a typewriting machine and has located therein, at a suitable point, a key lever mounting 2. This mounting comprises a bar secured transversely within the frame or casing 1 and provided intermediate of its ends with a plurality of notches 3. A flanged enlargement 4 projecting rearwardly from the central portion of the bar 2 is provided at its rear edge with a notched portion 5,—the notches in this portion corresponding in number and being in alinement with the notches 3 in the central portion of the bar. The bar 2 is also provided with a shorter bar 5^a which is spaced forwardly therefrom and disposed parallel therewith,—the lower edge of the shorter bar 5^a being connected with the main bar 2 by an integral connecting portion 6. The shorter bar 5^a is thus so disposed relatively to the main bar 2 that a groove is formed between said bars for the reception of a rod 7 and the said shorter bar is provided with a plurality of notches 8 corresponding in number and being in alinement with the notches 3 of the main bar 2.

The rod 8 serves to pivotally support a plurality of key levers 9, each of which is

provided at its inner or rear end with an upturned portion to which a suitable key button 10 is secured. The key levers are disposed, in front and in rear of their pivotal supports, within the notches 3 and 8 of the bars 5^a and 2 respectively, and each of said key levers is provided with a tail piece 11 projecting rearwardly from the pivotal support and passing through and guided in a notch 5 of the rearward enlargement 4. In this manner the key levers are effectively and accurately guided in their movements without danger of binding and furthermore the said key levers are prevented from undue lateral play, thus insuring the stability of the key lever structure as a whole as well also as the key board.

Each key lever is provided over its pivotal support with an upwardly projecting arm 12. A notched bar 13 is disposed transversely in the upper portion of the frame 1 and in this notched bar a plurality of type levers have pivotal supports between their ends. The lower arm of each type lever is slotted and pivotally connected with the upper end of the adjacent key lever arm 12, and the upper arm of each type lever is provided with a type 14. A platen 15 is located in operative relation to the types of the type levers, and between said type and the platen bar the ink- 85 ribbon and paper are fed. These features, however, form no part of my present invention and hence they are not shown in the drawing and need no further reference herein.

Having fully described my invention, what I claim as new and desire to secure by Letters Patent is:

1. In a typewriting machine, the combination of a plurality of key levers having upwardly projecting arms at their rear portions, pivotal mountings for the key levers at the junction of the arms therewith, a notched member in rear of and in close proximity to said mountings and tail pieces projecting rearwardly from the pivoted portions of said levers and guided in said notched member.

2. In a typewriting machine, the combination with a frame and a plurality of key levers having upwardly projecting arms at their rear portions, of a key lever mounting disposed within the frame and affording pivotal supports for the rear portions of the key levers at the junction of the upwardly 110

projecting arms therewith, said pivotal mounting having a notched member disposed rearwardly of and in close proximity to the pivotal mountings of the key levers 5 and receiving the latter rearwardly of and in close proximity to their pivotal supports.

3. In a typewriting machine, the combination with a frame, of a key lever mounting secured therein and provided with a plurality of notched portions disposed parallel with each other and having their notches in alinement, a plurality of key levers having upwardly projecting arms, pivotal mountings for said key levers located at the junction of the key levers and their arms and disposed between the forward parallel portions of said bearing, and each key lever provided with a rearwardly projecting tail piece hav-

ing its rear portion disposed in a notch of the rear notched portion of said bearing. 20

4. In a type writing machine, the combination of a plurality of L-shaped levers pivotally supported at the juncture of their two members and provided with extensions rearwardly of their pivotal supports, and guiding means coöperating with said rearward extensions and located in close proximity to the pivotal mountings of said levers. 25

In testimony whereof, I have signed this specification in the presence of two sub- 30 scribing witnesses.

WARD S. IRELAND.
